AUGUST HEINRICH MARHENKE, OF NEW YORK, N. Y.

LOCKING DEVICE FOR HAND-LEVERS.

1,159,973.

Specification of Letters Patent.

Patented Nov. 9, 1915.

Application filed July 1, 1914. Serial No. 848,374.

To all whom it may concern:

Be it known that I, AUGUST HEINRICH MARHENKE, a citizen of the United States, and a resident of the city of New York, borough of the Bronx, in the county of the Bronx and State of New York, have invented a new and Improved Locking Device for Hand-Levers, of which the following is a full, clear, and exact description.

10 Among the objects of the invention is to provide an attachment for hand levers with improved locking devices whereby the hand lever, when employed for the control of automobiles or the like, may be left locked in a 15 position or condition to baffle an attempt by any unauthorized person to move or disturb the machine.

The foregoing and other objects of the invention will hereinafter be more fully described and claimed and illustrated by the drawings forming a part of this specification in which like characters of reference indicate corresponding parts in all the views, and in which—

25 Figure 1 is a vertical view partly in elevation and partly in section, showing a preferred embodiment of the invention, the full lines indicating the normal position of the parts with the brake set but with the hand lever unlocked, and the dotted lines showing the hand lever disconnected from the brake connections and locked in inoperative condition; Fig. 2 is a vertical transverse section on the line 2—2 of Fig. 1; Fig. 3 is a vertical transverse detail on the line 3—3 of Fig. 1; and Fig. 4 is a detail view indicating the connecting and disconnecting means between the two main lever parts.

30 The several parts of this device may be made of any suitable materials, and the relative sizes and proportions, as well as the general design of the mechanism, may be varied to a considerable extent without departing from the spirit of the invention 35 hereinafter more fully described and claimed.

Referring more particularly to the drawings, I show a lever 10 pivoted on a horizontal axis 11. This lever is shown as of the 40 first class and having an arm 12 projecting downwardly and adapted for connection with brake mechanism or the like (not shown). The pivot 11 and the main portion of the lever 10 are housed within a

55 casing 13 shown as made preferably in two parts and having a slot 12' in its bottom through which the arm 12 extends. The casing is provided at its top with another slot 13' formed in the cylindrical surface having its axis coincident with the axis of 60 the pivot 11.

At 14 I show a hand lever having loose pivotal connection at 15 with the pivot 11. Any suitable means may be provided to detachably connect the hand lever 14 to the 65 lever 10, making them in effect a single lever whereby the operator in the manipulation of the hand lever may control the brake mechanism or any other device which may be connected to the arm 12. The hand lever 70 14 projects through the slot 13' and a guard 16 is fitted to the inner surface of the cylindrical top portion of the casing 13 and is manipulated by the hand lever, being of such a length that the slot 13' is maintained 75 effectively closed by the guard during all movements of the hand lever, and whereby access to the interior of the casing is prevented under ordinary conditions.

As shown in full lines in Fig. 1, the lever 80 and hand lever are normally in close fitting relation to each other and are thereby locked detachably by means of a hook 17 carried by and projecting laterally from a plunger 18 carried by the hand lever. The hook 17 85 extends into a socket 19 formed in the face of the lever 10 adjacent the hand lever and the hook, and while in the socket is adapted to engage with a catch or shoulder 20. The plunger is adapted to reciprocate longitudinally along the hand lever and under normal conditions is operated upon by a comparatively stiff spring 21, whereby the hook 17 is maintained in engagement with the catch 20. Under these conditions the lever 95 and hand lever are locked together and act as a single element.

At 22 I show a toothed segment secured in fixed position concentrically with the pivot 11 and with the teeth of which the lever 100 mechanism is adapted to coöperate when the brake is desired to be set either with the locking of the hand lever or without. I provide a pawl 23 having a point adapted to coact with the teeth of the segment 22. Said pawl is carried by the lever 10 and is adapted to reciprocate along the upper end of said lever toward or from the segment. As

shown in Fig. 1, the body portion of the pawl has a socket 24 providing for a sliding movement of the pawl along a lug 25 carried by the lever. The pawl may be acted upon by a spring 26, the normal tendency of which is to lift and hold the pawl out of engagement with the teeth of the segment. The plunger 18, however, is provided with a laterally projecting lug 27 which, when the plunger is depressed, causes the pawl to be forced downwardly into position to engage the teeth.

When the operator wishes to set the brake or manipulate any other machine part which may be connected to the arm 12, he will grasp the hand lever and draw it in the direction of arrow on Fig. 1. No action, however, of the pawl will take place unless the operator wishes to maintain the brake set and remove his hand from the handle 14^a of the lever. If he desires to maintain the brake set, he will depress the plunger 18 by applying his thumb to the upper end 18^a thereof which will cause the lug 27 to force the pawl 23 downwardly into engaging position with the segment 22. The plunger 18 may return to the normal position shown in Fig. 1, but the strain upon the lever 10 and pawl 23 incident to the action of the brake will maintain the pawl in engagement with the segment tooth. In order to release the pawl, therefore, for starting the machine, the operator has but to grasp the hand lever and exert a slight pressure upon it in the direction of the arrow so as to relieve the friction between the point of the pawl and the segment teeth. The spring 26 will then throw the pawl out of the path of the teeth, leaving the lever mechanism free for any desired manipulation.

The plunger 18 is provided at any convenient place, preferably adjacent the handle 14^a, with a notch or opening 18' which, when the plunger is in locking position, is adapted to register with a socket 28 having its axis substantially at right angles to the axis of the plunger. A locking bolt 29 is seated in said socket 28. A spring 30 seated in the outer end of the socket 28 acts normally upon the bolt 29 and tends to force the end of the bolt into the notch or hole 18', as shown in dotted lines in Fig. 1. The tendency of the bolt 29 to enter the hole 18' is normally resisted by a detent 31 arranged at right angles to the bolt 29 and seated normally in a notch 29' formed in one face thereof. The detent 31 is maintained in its normal position by means of a spring 32 but is movable out of normal position against the force of the spring 32 by means of a head 33 projecting beyond the hand lever in position to be engaged by the operator's thumb or finger. The bolt 29 has a shank 34 extending laterally or downwardly therefrom through which a key controlled screw 35 ex-

tends. The threads of the screw 35 are preferably of 45 degree pitch whereby either of the parts is adapted to operate the other. The screw, therefore, being normally free to rotate, will not resist the automatic movement of the bolt 29 under the force of its spring 30 when the detent 31 is pushed by the operator's thumb or finger. If, therefore, the operator desires to be absent from his machine and wishes to maintain the brake set, he will not only depress the plunger into position to set the pawl, but will also actuate the detent 31. The detent may be pushed either before or after the plunger is depressed. If pushed before, the bolt 29 will move a short distance until it strikes the plunger, such movement being far enough for the detent to be received against the side of the bolt and held from returning into the notch 29'. If, then, the plunger be depressed subsequently, the spring 30 will force the bolt directly into the hole 18'. In this position of the plunger the lug 27 will be in position to prevent the pawl 23 from moving out of engagement with the tooth against which it has been set, and at the same time the hook 17 will be detached from the catch 20. A stranger, therefore, upon grasping the hand lever will find it set free from the lever 10 and brake mechanism and he will be helpless to release the brake or manipulate the machine. The operator, however, or any authorized person having a key may insert it into the barrel 36, and upon turning the same will cause the screw 35 to withdraw the bolt out of locking position and cause the detent to snap into the notch 29' and the bolt will be so held until the detent is again actuated.

The principal reason for providing a pawl which is adapted to slide for ordinary purposes rather than pivoting it on a fixed pivot is to permit the pawl to tilt around the lug 27 as a pivot should it be desirable or necessary to apply force to the main lever when the hand lever is loose and locked. In this operation the point of the pawl may ride idly over the teeth of the segment 22 while the opposite portion of the pawl may slide freely toward the segment against the tension of the spring acting thereon.

Having thus described my invention, I claim as new and desire to secure by Letters Patent:—

The herein described locking device for a hand lever having a lock casing, a plunger, reciprocable along the hand lever and having a notch, a bolt movable longitudinally of said casing at right angles to the plunger, a detent holding the bolt normally out of contact with the plunger irrespective of the longitudinal movements of the plunger, means acting, however, against the outer end of the bolt tending to force it into engagement with the plunger whereby when

the detent is released the bolt will snap into the plunger notch, said bolt having a shank extending from one side thereof, and a key controlled screw acting through said shank 5 to withdraw it into idle position where it will be held by said detent, substantially as set forth.

In testimony whereof I have signed my name to this specification in the presence of two subscribing witnesses.

AUGUST HEINRICH MARHENKE.
